UNITED STATES PATENT OFFICE.

HUGH D. MACPHERSON, OF SUMMIT, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed March 4, 1922. Serial No. 541,219.

To all whom it may concern:

Be it known that I, HUGH D. MACPHERSON, a citizen of the United States of America, residing at Summit, in the county 5 of Union, State of New Jersey, have invented certain new and useful Improvements in Telephone Systems, of which the following is a full, clear, concise, and exact description.

10 This invention relates to improvements in transmission systems where it is desired to determine which one of a plurality of lines has been seized and has particular reference to a signaling system wherein signals for a 15 plurality of toll transmission lines extending between widely separated offices are controlled over a signaling path common to such lines.

In systems of this character wherein a 20 large number of toll lines have been employed, it has heretofore been proposed to transmit the codes of impulses over the common signaling path by means of start-stop distributors. The codes of impulses, upon being 25 transmitted, are translated to select a particular toll line at the receiving station whereupon a signaling device individual to said line is operated. Such systems have been found to be satisfactory in the results 30 attained where installed in offices of large capacity, but in localities where only a comparatively few lines are employed, the installation of said systems has not been deemed feasible.

35 Other systems have been designed wherein relay mechanism is used to transmit code impulses of current over physical and phantom lines having a signaling path connected thereto and common to said lines.

40 In some systems such as above referred to, should calls be initiated simultaneously on two or more lines, or should one or more of said lines be taken for use contemporaneously with the operation of the impulse 45 transmitting mechanism, the code of impulses being transmitted by said mechanism, will be effective to cause the operation of only one signaling device at the terminating or called office, and at the completion of the 50 transmission of said code, the transmitting mechanism will again be operated to send a series of impulses individual to one of the other lines upon which another call has been initiated. In this manner a plurality of

series of impulses must be successively transmitted for each line taken for use. 55

An object of the present invention is to determine which one of a plurality of transmission lines has been seized at a distant point. The inventive idea embodied in this 60 object is applicable for instance to telephone or printing telegraph systems. The object is accomplished by the method and means which comprise generating an electrical effect individual to each of a plurality of 65 transmission lines, modifying one or more of said effects in response to the seizure of one or more of said lines and transmitting the modified effects to identify the corresponding lines. 70

A feature of the invention comprises transmitting over a signaling path an impulse for each of a plurality of circuits adapted to be seized and in response to the seizure of any one of a plurality of said 75 circuits.

Another feature of the invention is the provision of impulse transmitting and receiving mechanisms, each preferably including a train of relays operable, when a call is 80 initiated on any one of a plurality of transmission lines, to transmit and receive, respectively, a series of impulses, of which one is characterized by the busy condition 85 of the line taken for use to effect the operation of a signaling device individual to said line. If calls are initiated simultaneously, or on certain of said lines contemporaneously with the transmission of a series of impulses, certain impulses of the series will be 90 so characterized as to cause the successive operation of signaling devices individual to the lines taken for use.

Another object is to render more positive the transmission of impulses over a signaling 95 path common to a plurality of toll transmission lines by preventing the transmission of an impulse until an impulse is received indicating that the first-named impulse may be properly received at a distant point. This 100 object is preferably accomplished by the method and means which comprise transmitting an impulse over a signaling path, receiving said impulse and, in response to the receipt of said impulse, transmitting a second impulse to control the transmission of a third impulse over said path. 105

The above and other objects, not specifi-

- cally mentioned, will be more clearly understood by reference to the following description when taken in connection with the accompanying drawings wherein Figs. 1 to 5 inclusive, when arranged in accordance with Fig. 8, illustrate one embodiment of the inventive idea, and Figs. 1, 4, 5, 6 and 7, arranged as shown in Fig. 9, disclose another embodiment thereof.
- 10 Briefly, the invention contemplates the provision of a plurality of transmission lines, such as L1, interconnecting two distant offices X and Y. Impulse transmitting and receiving mechanisms are provided at 15 each office and are operable to transmit and receive series of impulses over a common signaling path joining said offices. These series of impulses upon being received at office Y are utilized to control the operation 20 of signaling devices, such as guard lamps, each individual to one of the transmission lines. The transmitting and receiving mechanisms each comprise a train of relays, certain of which are arranged in groups, 25 each group being individual to one of the transmission lines. Upon the initiation of a call on any one of the transmission lines at office X, the transmitting mechanism thereat is operated to send a series of current 30 impulses over the common signaling path to the receiving mechanism at office Y, whereby the groups of relays comprising said receiving mechanism are successively operated. When the groups of relays 35 of the transmitting and receiving mechanisms individual to the line taken for use are reached in the operation of said mechanisms, an impulse of current of different potential from those transmitted for lines 40 which have not been taken for use is sent over the signaling path, and when this impulse is received by the receiving mechanism, the group of relays of the latter mechanism which is individual to said line, is in 45 such condition that said impulse of current will be effective to operate apparatus at the receiving office Y, which results in the lighting of the guard lamp individual to said line.
- 50 Should simultaneous calls be initiated on two or more of the lines, the groups of relays of the transmitting and receiving mechanism individual to the lines taken for use will operate together with the other groups, 55 and as each group of relays of said mechanisms associated with the busy lines is energized, an impulse of current similar to the one above referred to is transmitted over the signaling path. Through the intermediary of the receiving mechanism, said impulses cause the successive operation of the signaling devices or guard lamps individual to the various busy lines.
- 60 If, after a call has been initiated on one 65 line and the impulse transmitting and re-

ceiving mechanisms have started their operations of transmitting and receiving a series of impulses, other lines which are subsequent to the first named line in the order of their appearance should be taken 70 for use contemporaneously with the operation of said mechanisms, the character of the impulses of said series will be so changed by the seizure of said lines that said series will be effective to cause the operation of 75 signaling devices individual to all of the lines upon which calls have been initiated.

It is believed that the invention will now be clearly understood from the following 80 detailed description. The operation of the 80 system arranged in accordance with Fig. 8 will first be described.

Operator at office X initiates a call to substation S at office Z.

85

The operator at office X, desiring to establish connection with the telephone line S at office Z communicates with the operator at office Y over an order wire circuit (not shown) to receive an assignment of an idle 90 toll or trunk line. The operator at office X, upon ascertaining from the operator at office Y that the connection to substation S is to be established over toll line L1 inserts plug 100 of cord circuit A into the 95 jack 101 of line L1. The cord circuit A, only a portion of which is shown, is of a well-known design, and it will be understood that previous to the insertion of the plug 100 into jack 101, the operator at office X has connected the answering plug of 100 said cord circuit with the calling subscriber's line. Upon engagement of the sleeve contacts of said plug 100 and jack 101, a circuit is established which is traceable from 105 grounded battery, through the winding of the marginal relay 102, sleeve contacts of plug 100 and jack 101, and the winding of relay 103, to ground. The relay 102, being marginal, does not operate at this time. Relay 103, in operating, establishes a circuit 110 extending from ground at the normal contacts of either of the relays 104 or 105 through the alternate contact of relay 103, the normal contact of relay 106, winding of 115 slow release relay 107, common conductor 108, and the winding of relay 200 of the transmitting mechanism at office X to grounded battery. Relays 107 and 200 operate in this circuit, the energization of the latter relay initiating the operation of the 120 impulse transmitting mechanism shown in Fig. 2. The operation of relay 107 connects the positive terminal of a battery to the right-hand alternate contact of said relay for a purpose which will appear in the course of the description. The operation of relay 103 also closes an energizing circuit 125 for relay 109 extending from grounded battery, through the winding and normal con- 130

tact of said relay, and alternate contact of relay 103 to ground at the normal contacts of either of the relays 104 or 105. Relay 109 operates and locks to ground through its 5 left-hand alternate contact, but performs no useful function at this time.

It is here noted that all slow operating and releasing relays shown in the drawings have been indicated conventionally by 10 arrows intersecting the armatures of these relays and pointing in the direction that the armatures move slowly.

Relay 200, in operating, closes a circuit 15 extending from ground, through the contact of relay 200, the contact of slow release relay 201, and the winding of relay 202 to grounded battery for operating relay 202. An obvious energizing circuit is also established for relay 203 by the operation of relay 200, and relay 203 thereupon locks to ground 20 at the normal contact of relay 204. When relay 202 operates, ground is connected to the upper left-hand contact thereof to establish an obvious operating circuit for slow 25 release relay 205. The closure of the contact of the latter relay causes the operation of slow release relay 201, which in opening its contact disconnects ground from the winding of relay 202, which then releases 30 to cause the release of relay 205, followed by the release of relay 201. When the contact of relay 201 again closes, relay 202 is again operated to once more initiate the cycle of 35 operation of relays 205 and 201. Each time that relay 202 is operated and released, an 40 impulse of current is transmitted over the common signaling path P to the receiving mechanism at office Y to accomplish the operation of relays of a train forming a part 45 of this receiving mechanism. The operation of relay 202 also causes the synchronous operation of relays of the train included in the transmitting mechanism at office X. The first energization of relay 202 establishes a 50 circuit extending from ground, through the lower left-hand contact of relay 202, and from thence in parallel over one path, through the left-hand normal contact of relay 208, the normal contact of relay 210, and the right-hand winding of relay 209 to 55 grounded battery, and over another path through the right-hand contact of relay 208 and the left-hand winding of this relay to grounded battery. The right-hand armature and contact of relay 208 initially shorts 60 circuits the right-hand winding of relay 208, but said relay operates through its left-hand winding, and is held operated through both of its windings in series by the ground at the lower left-hand contact of relay 202, while the latter relay remains operated. This arrangement of the circuit of relay 208 65 provides for the quick operation and release thereof to insure the proper operation of the train of relays comprising the trans-

mitting mechanism at office X. When relay 208 operates, ground is disconnected from the left-hand normal contact of said relay, but before this occurs, relay 209 energizes in the circuit traced therefor, and locks through 70 its left-hand winding and contact to ground at the left-hand contact of relay 206. The closure of the left-hand contact of relay 209 also establishes an energizing and holding circuit for relay 210, which in operating 75 transfers the conductor connected to the left-hand normal contact of relay 208 to the alternate contact of relay 210 to prepare an energizing circuit for relay 211. The closure of the right-hand alternate contact of 80 relay 209 connects a potential thereto which depends upon the condition of a relay associated with the first toll line (not shown), similar to relay 107 individual to the line L1. Assuming that the first toll line is 85 idle, it will be obvious that the relay associated therewith, which is similar to relay 107, is in its normal condition, and therefore ground will be connected to the right-hand alternate contact of relay 209. This ground 90 is extended through the normal contacts of the remaining relays of the train similar to relay 209, and thence to the right-hand normal contact of relay 206. While relay 202 is energized, this ground has no effect. The 95 closure of the right-hand alternate contact of relay 202, during the energization thereof, connects negative battery over one path, through the lower winding of the polarized 100 relay 207, and the artificial line to ground, and over another path through the upper winding of said polarized relay, and over the common signaling conductor P, the windings of the polarized relay 300 at office 105 Y, and the artificial line to ground. The 110 current in this path has no effect on the relay 207, but causes the relay 300 to close its upper contact, thereby establishing a circuit extending from ground, the upper contact of relay 300, from thence over one path 115 through the left-hand contact and right-hand winding of relay 301, similar to relay 208, to grounded battery, and over another path through the right-hand normal contact of relay 301, the normal contact of relay 304, and the left-hand winding of relay 303 to grounded battery. Relays 301 and 303 120 operate, the latter relay immediately locking through its right-hand winding and contact to ground at the contact of relay 302. Relay 301, in operating, provides a holding circuit for itself extending through both of its windings, and disconnects ground from its right-hand normal contact, which is extended to the left-hand winding of relay 303. The operation of relay 303 is followed by 125 the energization of relay 304 through the contact of relay 303. When relay 202 releases following the opening of its circuit by the energization of relay 201, relay 208 130

4

releases, and the ground which is connected to the right-hand normal contact of relay 206 is now extended to the normal contact of relay 202, and from thence to the windings of the polar relays 207 and 300. This ground causes relay 300 to release, and thus move its armature to its neutral position, thereby disconnecting ground from the upper contact of relay 300 to cause the release 10 of relay 301.

Upon the next energization of relay 202, due to the release of relay 201, ground connected to the lower left-hand contact of relay 202 is extended to the left-hand normal contact of relay 208, the alternate contact of relay 210, normal contact of relay 212, and the right-hand winding of relay 211 to grounded battery, causing the operation of the latter relay, which then locks through its 15 left-hand winding and contact to ground at the left-hand contact of relay 206. The ground connected to the lower left-hand contact of relay 202 also causes the operation of relay 208, as previously described, to 20 disconnect the ground from the left-hand normal contact of relay 208. The closure of the upper left-hand contact of relay 202 again initiates the cycle of operation of relays 205 and 201 to cause the release of relay 25 302. The operation of relay 211 in the circuit described therefor causes the energization of relay 212 over an obvious circuit, and the closure of the right-hand alternate contact of relay 211 connects a potential to 35 the right-hand normal contact of relay 206, which depends upon the condition of a relay associated with the first toll line, similar to the relay 110 individual of the toll line L1. This relay similar to 110, being in its normal 40 position, a ground potential is connected to the right-hand normal contact of relay 206. The operation of relay 212 connects ground in series through the right-hand normal contacts of relays 222, 220, 218, 216 and 45 214, the right-hand alternate contact of relay 212, to the left-hand contact of a relay associated with the first toll line, similar to relay 107. Since it is assumed that this relay associated with the first toll line is in 50 its normal condition, the ground has no effect.

The second operation of relay 202, again connects negative battery through the right-hand alternate contact of said relay to the 55 windings of the polar relays 207 and 300, thereby causing the latter relay to close its upper contact in the same manner as previously described. The ground connected to said upper contact is now extended through 60 the right-hand normal contact of relay 301, the left-hand alternate contact of relay 304, the left-hand normal contact of relay 306, and the left-hand winding of relay 305 to grounded battery, causing the operation of 65 the latter relay, which then locks through its right-hand winding and contact to ground at the contact of relay 302. The ground connected to the upper contact of relay 300 also energizes relay 301 to disconnect said ground from the winding of relay 305. 70 When relay 305 closes its contact, relay 306 operates over an obvious circuit, and is held operated by the ground at the contact of relay 302. When the relay 202 releases in the second cycle of operation of relays 201, 202 75 and 205, the ground which is connected to the right-hand normal contact of relay 206, through the right-hand alternate contact of relay 211, and the normal contact of the relay associated with the first toll line similar 80 to relay 110, is extended through the normal contact of relay 202, to the windings of the polar relays 207 and 300, causing the release of the latter relay, which is followed 85 by the deenergization of relay 301.

When relay 202 next operates to transmit the third impulse of current over the common signaling path P, the ground at the lower left-hand contact of relay 202 is extended through the left-hand normal contact of relay 208, through the left-hand alternate contacts of relays 210 and 212, the left-hand normal contact of relay 214, and the right-hand winding of relay 213 to grounded battery. Relay 213 operates in this circuit and locks in an obvious manner, and relay 208 energizes, as before described. The closure of the left-hand contact of relay 213 causes the energization of relay 214, while the closure of the right-hand alternate contact 90 of relay 213 connects positive battery from the right-hand alternate contact of relay 107, which is now operated, to the right-hand normal contact of relay 206, through the normal contacts of relays 215, 217, 219 95 in series. This battery potential has no effect until relay 202 releases. While the latter relay is operated, negative battery is connected to the windings of the polar relays 207 and 300, through the right-hand alternate contact of relay 202, causing the relay 300 to close its upper contact. The ground now connected to this contact is extended through the right-hand normal contact of relay 301, the left-hand alternate contacts of relays 304 and 306, the left-hand normal contact of relay 308, and the left-hand winding of relay 307 to grounded battery. Relay 307 energizes in this circuit and locks in an obvious manner, and after the 100 energization thereof, relay 301 operates as before described. The closure of the contact of relay 307 closes an obvious circuit for operating relay 308.

When relay 202 releases for the third 105 time during the operation of the impulse control relays, relay 208 deenergizes, and upon closure of the right-hand normal contact of relay 202, the positive battery connected to the right-hand alternate contact 110 115 120 125 130

of relay 107 is then extended through the right-hand normal contact of relay 206, the normal contact of relay 202, and the windings of polar relays 207 and 300 to ground through the artificial line. This positive impulse of current transmitted over the signaling path P causes the relay 300 to close its lower contact, thereby causing the release of relay 301. The ground now connected to the lower contact of relay 300 is extended to the right-hand normal contacts of relays 314, 312 and 310, right-hand alternate contact of relay 308, and from thence in parallel through the middle winding of the differential relay 400, and the left-hand winding of relay 401 to the grounded battery. Relays 400 and 401 operate in this circuit, and the former locks through its right-hand winding. The effect of the operation of these two relays will presently be described.

The fourth energization of relay 202 in the cycle of operation of the impulse control relays now connects ground from the lower left-hand contact of relay 202, through the left-hand normal contact of relay 208, the alternate contact of relay 210, the left-hand alternate contacts of relays 212 and 214, the left-hand normal contact of relay 216, and the right-hand winding of relay 215 to grounded battery. Relay 215 energizes and locks, and by the closure of its left-hand contact causes the energization of relay 216. When the latter relay closes its right-hand alternate contact, a circuit is established for relay 106 extending from grounded battery, through the winding of said relay, the left-hand contact of relay 107, right-hand alternate contact of relay 216, and the right-hand normal contact of relays 218, 220, and 222 in series, to ground. Relay 106 energizes and locks through its winding and left-hand contact, the alternate contact of relay 103, and left-hand normal contact of relay 105, to ground. In opening its alternate contact, relay 106 breaks the holding circuit for relays 107 and 200, and these relays thereupon release. The release of relay 107 disconnects positive battery from the right hand normal contact of relay 206. The release of relay 200 removes the control of the operation of the relay 202 from the relay 200 and transfers it to relay 204, which has ground connected to its normal contact. This ground controls the succeeding operations of relay 202, as will presently appear. The operation of relay 202 again connects negative battery to the right-hand alternate contact thereof to cause the polar relay 300 to close its upper contact, whereupon the ground connected to this contact is extended through the right-hand normal contact of relay 301, the left-hand alternate contacts of relays 304, 306 and 308 in series, the left-hand normal contact of relay 310 and the left-hand winding of relay 309 to grounded battery. Relay 309 operates and locks, and in closing its contact establishes an obvious energizing circuit for relay 310. Relay 310 again operates following the closure of the circuit for relay 309 and disconnects the ground at the upper contact of relay 300 from the right-hand normal contact of relay 301. When relay 202 releases for the fourth time, relay 208 deenergizes, and upon closure of the normal contact of relay 202, ground is connected through the normal contact of relay 110, the right-hand alternate contact of relay 215, the normal contacts of relays 217 and 219, right-hand normal contact of relay 206, normal contact of relay 202, and from thence to the windings of polar relays 207 and 300, causing the latter relay to restore its armature to its neutral position and thereby disconnect ground from the upper contact thereof, causing the release of relay 301.

Relay 202 now operates for the fifth time, and the circuit therefor in this and succeeding operations extends from grounded battery, through the winding of relay 202, contact of relay 201, contact of relay 203, which is energized and locked, and the normal contact of relay 204 to ground, relay 200 being now released, as previously described. When relay 202 closes its lower left-hand contact, relay 217 operates and locks in a manner, which is now believed to be obvious from an understanding of the description of the operation of other similar relays, and upon energization of relay 217, relay 218 operates. Relay 208 energizes in the same manner as before described. The operation of relay 202 again connects negative battery to the right-hand alternate contact of said relay to transmit an impulse of current of negative polarity over the path P to cause polar relay 300 to close its upper contact. In a manner which is now believed to be obvious, connection of ground to the upper contact of relay 300 causes the operation and locking of relay 311 and the energization of relays 312 and 301. When relay 202 releases for the fifth time, the ground which is found at the normal contact of the relay associated with the last toll line similar to the relay 107 of line L1, is extended through the right-hand alternate contact of relay 217, the normal contact of relay 219, the right-hand normal contact of relay 206, the normal contact of relay 202, and from thence to the windings of the relays 207 and 300, causing the latter relay to open its upper contact, following which relay 301 releases.

The sixth energization of relay 202 is followed by the energization and locking of relay 219 and the operation of relays 208 and 300.

220 in a manner which is now believed to be obvious. The operation of relay 202 causes relay 300 to again close its upper contact, whereby relays 313, 314 and 301 are operated. The sixth release of relay 202 causes the deenergization of relay 208 and the connection of ground from the normal contact of the relay associated with the last toll line similar to relay 110, to the right-hand alternate contact of relay 219, from whence said ground is extended through the right-hand normal contact of relay 206 and normal contact of relay 202 to the windings of relays 207 and 300, causing the latter relay 15 to open its upper contact, following which relay 301 again releases.

The seventh and last operation of relay 202 effects the operation of relays 221, 222 and 208, and when relay 222 energizes, an obvious operating circuit for relay 204 is established. The latter relay energizes to open the locking circuit of relay 203, which then releases to permanently open the energizing circuit of relay 202 so that this 25 relay will not again operate after its seventh release. The closure of the alternate contact of relay 204 causes the energization of relay 206, which, in disconnecting ground from its left-hand contact, opens the locking and holding circuits of relays 209 to 222, inclusive, whereupon these relays restore to normal. The deenergization of relay 222 opens the circuit for relay 204, which then releases, followed by the release 30 of relay 206. However, before this action takes place, relay 300 is caused to again close its upper contact by the energization of relay 202 so as to bring about the operation of relays 315, 301 and 302 over circuits 35 which are now believed to be obvious. When relay 302 operates, the ground is disconnected from the contact thereof to open the holding and locking circuits for relays 303 to 315, inclusive, and these relays thereupon 40 restore to normal. When relay 302 operates, it interrupts its own energizing circuit, and hence said relay will immediately de-energize. When relay 202 releases for the seventh time, ground is connected to the normal contact thereof from the alternate contact of relay 206, which has not yet released, 45 and this ground causes relay 300 to open its upper contact, thereby restoring relay 301. The cycle of operation of the trains of 50 transmitting and receiving relays has now been completed, and a series of impulses individual to the line L1 has been transmitted over the common signalling path P and received at office Y in such a manner as to select mechanism thereat individual to the line L1.

Returning to a point in the operation where relays 400 and 401 were operated by the connection of ground to the lower contact of relay 300, and relay 400 was locked,

it will be obvious that relay 401 is not locked after its energization due to the fact that relay 402 is not operated. Therefore, as soon as the impulse of current has been terminated and the lower contact of relay 300 50 is opened, as described, relay 401 restores, thereby establishing a circuit for the slow release relay 403 from grounded battery through the winding of relay 403, the normal contact of relay 401 and the right-hand alternate contact of relay 400 to ground. Relay 403 energizes and establishes an obvious operating circuit for the slow release relay 402. The operation of relays 402 and 403 have no effect at this time. When relay 400 operates, guard lamp 404 individual to line L1 is lighted over a circuit extending from grounded battery, through the lamp 404, the right-hand normal contact of relay 405 and the right-hand alternate contact of 55 relay 400 to ground. The lighting of the lamp 404 serves as a signal to the operator at office Y, indicating that the operator at office X has connected the cord circuit A to the proper toll line L1. 90

Connection of toll switching trunk circuit M with the telephone line S.

At the time that the operator at office Y designated the toll line L1 with which the operator at office X should connect the cord circuit A, the operator at office Y also communicated with the operator at office Z over an order wire circuit (not shown), informing the operator at office Z as to the number of the desired line, whereupon the operator at office Z designates the toll switching trunk circuit over which the connection should be established. Assuming the toll switching trunk M to be that designated, the operator at office Z, after designating this trunk, inserts the plug 500 into the jack 501 of the telephone line S. Relays 502 and 503 then operate over an obvious circuit, through the sleeve contacts of plug 500 and jack 501. 100 The operation of relay 503 disconnects the line relay 504 from the telephone line, and thus prevents the operation of said relay and consequent lighting of line lamp 505 when the subscriber at the called substation removes his receiver from its switch hook in answer to the ringing of his call bell. The operation of relay 502 establishes a circuit for the supervisory lamp 506 extending from grounded battery, through the lamp 506, the right-hand alternate contact of relay 502, resistance 507, and the normal contact of relay 508 to ground. 115

Operator at office Y connects toll line L1 to the toll switching trunk M.

When the operator at office Y observes the lighted condition of guard lamp 404, she inserts plug 407 into jack 408 of the toll switching trunk M, and thereby causes the 130

successive energizations of relays 406 and 405 over obvious circuits. The energization of the latter relay opens its right-hand normal contact, and thereby extinguishes the 5 lamp 404. The operation of relay 405 also establishes a circuit for the supervisory relay 410 and the relay 508 in the trunk circuit M, said circuit being traceable from grounded battery, through the left-hand 10 winding of relay 508, outer normal contact of relay 509, the tip contacts of jack 408 and plug 407, the left-hand alternate contact of relay 405, the upper normal contact of relay 409, winding of the supervisory relay 410, 15 the outer left-hand alternate contact of relay 400, the lower normal contact of relay 409, ring contacts of plug 407 and jack 408, the inner normal contact of relay 509, and the right-hand winding of relay 508 to ground. 20 The energization of relay 508 opens the circuit of and extinguishes the lamp 506. The energization of the supervisory relay 410 establishes a circuit extending from ground, through the alternate contact of this 25 relay, and from thence in parallel over one path through the winding of slow release relay 411, over another path through the left-hand contact of relay 411, the normal contact and winding of slow release relay 30 412, and over a third path through the winding of slow release relay 419 to grounded battery. Relays 411, 412 and 419 energize, and relay 412 is then locked through its winding and right-hand alternate contact 35 to ground. The operation of relay 419 has no effect at this time. The closure of the left-hand contact of relay 412 establishes an obvious energizing circuit for relay 413, which then locks through its winding 40 and left-hand alternate contact to ground. The ground connected to the left-hand contact of relay 412 is also extended through the winding of slow release relay 414, and from thence over the common conductor 417 45 to battery through the winding of a relay in the transmitting mechanism TM, similar to the relay 200. This relay and relay 414 energize in this circuit, and the energization of the former initiates the operation of the 50 transmitting mechanism TM, which is similar in all respects to the mechanism shown in Fig. 2. The relays of the mechanism TM are now operated to transmit a series of impulses over the signalling path P to the receiving mechanism RM at office X in the same manner as described in connection with the transmission of impulses from office X to office Y. The receiving mechanism RM at office X is identical with that of office Y, 55 illustrated in Fig. 3, the relays of the mechanism RM being controlled by the polarized relay 207. When the relay in the transmitting mechanism TM at office Y, similar to the relay 216, operates, ground from the normal contact of a relay similar to relay 222 60 is connected to conductor 316, and extended through the alternate contact of relay 414 to short circuit relay 412 and this relay thereupon releases to remove ground from the windings of relay 414 and the relay of 70 the mechanism TM, similar to the relay 200, whereupon these relays deenergize. Before this occurs, however, the positive battery connected to the left-hand alternate contact of relay 414 causes the relay 207 to close 75 its lower contact and thereby connect ground to the conductor 223, through the right-hand alternate contact of a relay of the receiving mechanism RM, similar to relay 308. Following this, the remaining relays of the 80 transmitting and receiving mechanisms TM and RM are operated and released in the same manner as described in connection with Figs. 2 and 3. The ground connected to the conductor 223 causes the operation of the differential relay 112 and relay 115, the former relay locking to ground through its left-hand winding and contact, the alternate contact of relay 103, and the left-hand normal contact of relay 105. The relay 115, 85 however, does not lock inasmuch as relay 114 is deenergized at this time, and relay 115 therefore restores at the termination of the impulse which caused relay 207 to close 90 its lower contact. Upon the closure of the right-hand contact of relay 115, a circuit is established for slow release relay 113, extending from grounded battery, through the winding of said relay, right-hand contact of relay 115, left-hand contact of relay 100 112, and from thence to ground over the locking circuit of the latter relay. The operation of the relay 113 causes the energization of slow release relay 114 over an obvious circuit. When the contact of relay 105 105 114 is closed, a circuit is established extending from ground, through said contact, the left-hand normal contact of relay 115, the right-hand contact of relay 105, resistance 111, sleeve contacts of jack 101 and plug 110 100, and the winding of marginal relay 102 to grounded battery. The inclusion of the resistance 111 in this circuit, in parallel with the winding of relay 103, permits relay 102 115 to energize, and in so doing an obvious circuit is established for lighting the lamp 117. The lighting of this supervisory lamp serves as a signal to the operator at office X that the connection has been completed through 120 to the wanted line, and that the circuit is now in condition for operating the call bell at the substantion S.

Operator at office X actuates the ringing key. 125

The operator at office X upon observing the lighted condition of the lamp 117, now actuates ringing key 118, and thereby connects a source of ringing current to the tip and ring contacts of the jack 101 and plug 130

100, which operates the ringing response relay 104 bridged across the line L1. Relay 104, in closing its alternate contact, establishes an obvious energizing circuit for slow release relay 105. The opening of the left-hand normal contact of relay 105 breaks the locking circuit for relay 106, which thereupon releases. The locking circuit for relay 112 is also temporarily opened by the energization of relays 104 and 105, but relay 112 does not release before the alternate contact of relay 105 is closed, and therefore relay 112 will remain in its locked condition. The opening of the right-hand contact of relay 105 causes the release of marginal relay 102 and the extinguishing of the supervisory lamp 117. When the operator releases the ringing key, relays 104 and 105 release, whereupon the marginal relay 102 is again operated to light the lamp 117.

When relay 106 releases at the time relay 105 is energized, a circuit is established extending from ground, through the alternate contacts of relays 105 and 103, and from thence over the previously described energizing circuit of relays 107 and 200. Relays 107 and 200 again energize to initiate the operation of the transmitting mechanism at office X to transmit over the common signaling path a series of current impulses identical with the series which was originally sent at the time the call was initiated. The circuit for relays 107 and 200 is maintained after the operator restores the ringing key 118 to normal, since ground is connected to the normal contact of relay 104 and hence to the windings of relays 107 and 200 before the relay 105 opens its alternate contact. During the operation of the transmitting mechanism at office X, relay 106 is again operated and locked, and relays 107 and 200 deenergized, as previously described. The series of impulses now transmitted is received by the mechanism at office Y, and when relay 308 of this mechanism is operated and relay 300 closes its lower contact, ground is connected to the middle winding of relay 400 and the left-hand winding of relay 401. Relay 400 is unaffected since said relay is already locked, but relay 401 is energized by this ground, and since relays 402 and 403 are now operated, relay 401 locks through its right-hand winding and contact to ground at the contact of relay 402. Upon the closure of the alternate contact of relay 401, a circuit is established extending from ground, through the contact of relay 402, the alternate contact of relay 401, and from thence in parallel through the windings of slow release relays 415 and 409 to grounded battery. These relays operate, and the former in connecting ground to its contact, establishes a temporary holding circuit for relay 411 and energizes relay 419. Relay 409, in operating, connects a source of ringing current to the tip and ring contacts of plug 407 and jack 408 to operate the ringing response relay 510 of the toll switching trunk M. When relay 409 opens its normal contacts, the circuit for the supervisory relay 410 is opened and this relay thereupon releases, but inasmuch as relays 411 and 419 are maintained energized by the energization of relay 415, the ground connected to the front contact of relay 410, upon release of this relay, has no effect at this time. The energization of relay 409 also opens the circuit for relay 508, but before this relay can release, a temporary holding circuit is provided therefor, extending from grounded battery, through the left-hand winding of relay 508, the outer normal contact of relay 509, tip contacts of jack 408 and plug 407, the left-hand alternate contact of relay 405, and the upper alternate contact of relay 409 to ground. When relay 401 operates, the holding circuit for slow release relay 403 is opened, and this relay, after an interval, releases to open the holding circuit for slow release relay 402, which in releasing disconnects ground from the locking winding of relay 401 and the windings of relays 415 and 409. Due to the slow release nature of relays 402, 403 and 409, a sufficient time interval is provided for proper application of ringing current to the called line. The release of relay 402 is followed by the release of relay 401, whereupon relays 403 and 402 again operate. During the time that relays 409 and 415 are operated, relay 510 remains energized, and the closure of the contact of this relay establishes a circuit extending from ground, through said contact, winding of the ringing relay 511, and the left-hand winding of relay 509 to grounded battery. Relays 509 and 511 energize in series, and the operation of the former provides a holding circuit for relay 508 extending from grounded battery, through the left-hand winding of relay 508, to ground at the alternate contact of relay 509, thereby maintaining the relay 508 in its operated condition and preventing the lighting of the lamp 506. The operation of relay 511 connects ringing current to the telephone line S to operate the subscriber's signal or call bell. When ringing relay 409 releases, ringing current is disconnected from the toll switching trunk M and ringing response relay 510 releases, causing the deenergization of relay 509 and the ringing relay 511. The release of relay 509 connects both windings of relay 508 in circuit with the supervisory relay 410 before the holding circuit established by the operation of relay 509 is opened at the alternate contact of the latter relay. Thus the relay 508 remains in its energized condition. The deenergization of relay 511 disconnects ringing current from the line S. The series circuit

cuit for relays 508 and 410, being again established, the latter relay operates to again close its alternate contact before the slow release relays 411 and 419 can close their contacts following the opening of the temporary holding circuit for said relays by the release of relay 415, and therefore relays 411 and 419 will remain operated over the circuit to ground at the alternate contact 10 of relay 410. This operation of ringing the signal at substation S may be repeated until the subscriber thereat removes his receiver from the switch hook.

15 *The subscriber at substation S removes his receiver from its switch hook.*

In response to the operation of the signal at substation S, the subscriber thereat removes his receiver from its switch hook, thereby causing the operation of the supervisory relay 512 over a circuit extending from grounded battery, through the winding of said relay, the upper normal contact of relay 511, the tip contacts of plug 500 and jack 501, the apparatus at substation S, the ring contacts of jack 501 and plug 500, the left-hand alternate contact of relay 502, and the lower normal contact of relay 511 to ground. Relay 512 operates and causes the energization of relay 509 over a circuit extending from grounded battery, through the left-hand winding of relay 509, the contact of relay 512, the right-hand winding of relay 509, and the alternate contact of relay 508 to ground. Relay 509, in operating, closes its alternate contact and opens its normal contacts, whereby relay 508 is disconnected from the circuit including the supervisory relay 410, relay 508 being again held 35 operated by closure of the alternate contact of relay 509. The operation of relay 509 causes the release of the supervisory relay 410, whereupon the holding circuit for slow release relays 411 and 419 is opened and said 40 relays, after an interval, release. It will be recalled that relay 413 was operated and locked at the time that line L1 was connected to the trunk M and a series of impulses sent to office X to light lamp 117 as 45 a ringing signal, and therefore at this stage of the operation, with relays 410, 411 and 419 released, a circuit is established extending from ground, through the normal contact of relay 410, the right-hand contact of relay 411, the contact of relay 419, the right-hand contact of relay 413, winding of relay 416, and from thence over the common conductor 417 to grounded battery through the winding of the relay in the transmitting mechanism TM, similar to relay 200. This relay and relay 416 are operated, and the transmission of a series of impulses by the mechanism TM over the common signaling path P to the mechanism RM is thereby 50 initiated. When the relay in the transmit-

ting mechanism TM, similar to the relay 215, is energized, and the impulse control relay of said mechanism, similar to relay 202, is released, positive battery is connected through the left-hand alternate contact of relay 416 to the conductor 418, and from thence through contacts of said relays in the transmitting mechanism TM, similar to relays 215 and 202, and through the polar relays 300 and 207 to ground. The impulse thus transmitted causes the polar relay 207 to close its lower contact, whereby ground is connected to the conductor 224 through contacts of relays in the receiving mechanism RM, similar to relays 314, 312 and 310, the latter being now energized at this stage of the operation. This ground connected to the conductor 224 is extended through the right-hand contact and right-hand winding of relay 112 to grounded battery. The middle and right-hand windings of relay 112 being differentially wound, the closure of the circuit through the right-hand winding causes relay 112 to release. The opening of the left-hand contact of relay 112 is followed by the release of relays 113 and 114. The removal of ground from the contact of the latter relay opens the energizing circuit, through the resistance 111, of the marginal relay 102, whereupon relay 102 restores to 55 extinguish the lamp 117, thus indicating to the operator at office X that the subscriber at substation line S has answered the call.

During the transmission of the series of impulses, which results in the extinguishing of lamp 117, ground is connected to conductor 317 by the operation of a relay in the mechanism TM, similar to the relay 218, the right-hand alternate contact of which is connected to the left-hand contact of relay 110, which corresponds to the relay 416 at office Y. This ground, which is connected to conductor 317, short circuits the relay 413 and thereby causes the release thereof. The release of relay 413 opens the circuit for 60 relay 416 and the relay in the transmitting mechanism TM, similar to relay 200, and these relays thereupon restore.

Subscriber at substation S replaces his receiver upon the switch hook.

At the termination of the conversation, the subscriber at substation S restores the receiver to the switch hook, thereby releasing the supervisory relay 512, and when the contact of the relay is opened, relay 509 releases to close its normal contacts. When this occurs, the relays 508 and 410 are again placed in series, and relay 410 operates to close its alternate contact. At this time relays 411 to 416 and 419 are deenergized, and the closure of the alternate contact of relay 410 will therefore establish the previously described energizing circuits for relays 411, 412, 413 and 419, the relays 412 65 70 75 80 85 90 95 100 105 110 115 120 125 130

and 413 then being locked. When relay 412 closes its left-hand contact, the previously described circuit for relay 414 and the relay of the transmitting mechanism 5 TM, similar to relay 200, is again closed to initiate the operation of the transmitting mechanism TM, whereby a series of impulses will be transmitted over the common signaling path to control the operation of 10 the receiving mechanism RM at office X. This series of impulses is similar to the one transmitted at office X when the line L1 was connected to the toll switching trunk M, and results in the grounding of the conductor 223 when the relay of the mechanism RM, similar to relay 308, is operated. Relays 112 and 115 being now released, respond to the grounding of the conductor 223, and relay 112 locks as before, but relay 15 20 25 30 35 40 115 releases at the termination of the impulse since relay 114 is not at this time energized. The energization of relay 112 causes the successive operation of relays 113 and 114 as soon as relay 115 closes its right-hand contact, and when relay 114 now operates, the resistance 111 is again included in the circuit of the marginal relay 102, causing this relay to operate and light the lamp 117, thus indicating to the operator at office X that the subscriber at substation S has replaced his receiver upon its switch hook. During the transmission of this series of impulses, relays 412 and 414 are released, as previously described, and at the termination of the transmission of the series of impulses, the transmitting and receiving mechanisms TM and RM are restored to normal in a manner which is now believed to be well understood.

40 Operator at office X disconnects cord circuit A from Line L1.

The operator at office X, upon observing the lighted condition of lamp 117, now removes the plug 100 from the jack 101, causing the release of relays 102 and 103, and the extinguishment of the lamp 117. The release of relay 103 opens the locking circuit of relay 106, which is energized at this 45 time, and this relay thereupon releases. The release of relay 103 opens the locking circuit of relay 112 and the holding circuit for relay 113. These relays thereupon release, and the release of the latter relay 50 55 60 65 70 75 80 85 90 95 100 105 110 115 120 125 130 causes the deenergization of relay 114. Relay 109 is energized and locked at this time, and therefore the release of relay 103 establishes a circuit extending from ground at the left-hand normal contact of relay 105, through the normal contact of relay 103, the right-hand contact of relay 109, the winding of slow release relay 110, common conductor 108, and the winding of relay 200 to grounded battery. Relays 200 and 110 operate, and the energization of the

former again initiates the operation of the transmitting mechanism at office X to transmit a series of impulses over the common signaling path P to the receiving mechanism at office Y. It will be noted that during the transmission of this series of impulses, positive battery is not connected to the right-hand alternate contact of relay 213 as in the case of the first series of impulses transmitted, since relay 107 is now released. However, positive battery is connected, due to the energization of relay 110, to the right-hand alternate contact of relay 215 so that after relay 215 has been energized during the operation of the transmitting mechanism, and when relay 202 next releases following the energization of relay 215, the positive battery connected to the right-hand alternate contact of relay 110 is extended over the common signaling path P to cause the relay 300 to close its lower contact. At this time, relay 310 of the receiving mechanism has been operated, and the ground connected to the lower contact of relay 300 is therefore extended to the right-hand normal contacts of relays 314 and 312, the right-hand alternate contact of relay 310, and the inner left-hand contact and left-hand winding of differential relay 400 to grounded battery. The left and middle windings of relay 400 being differentially wound, the closure of the circuit through the left-hand winding thereof causes this relay to release. The effect of the release of this relay will presently be described.

When relay 218 of the transmitting mechanism at office X operates, ground at the normal contact of relay 222 is extended through the right-hand normal contact of relay 220, the right-hand alternate contact of relay 218, the left-hand contact of relay 110 to the winding of relay 109, thereby short circuiting relay 109 and causing the same to release. The opening of the right-hand contact of relay 109 breaks the circuit for relays 200 and 110, and these relays thereupon restore. The operation of the remaining relays in the transmitting mechanism at office X is then under the control of relay 204, as previously described. At the termination of the transmission of the series of impulses, which results in the deenergization of relay 400, the entire mechanism at office X is again in its normal condition.

The release of relay 400 results in the deenergization of relays 403 and 402, and upon closure of the normal contact of relay 400, a circuit is established extending from ground, through the normal contact of relay 400, the right-hand alternate contact of relay 405, and the lamp 404 to grounded battery. The lamp 404 is lighted in this circuit to indicate to the operator at office Y

50

1,550,830

11

that she may now withdraw the plug 407 from engagement with jack 408 of the toll switching trunk M.

At the time that relay 400 opens its outer 5 left-hand contact, supervisory relay 410 releases. When this relay deenergizes relays 411 and 419 release and a circuit is established extending from ground, through the normal contact of relay 410, the right-hand 10 contact of relay 411, the contact of relay 419, the right-hand contact of relay 413, winding of relay 416, and from thence over the common conductor 417 to grounded battery, through the winding of the relay in the 15 transmitting mechanism TM, similar to relay 200. The closure of this circuit operates relay 416 and the relay similar to relay 200 to initiate the operation of the transmitting and receiving mechanisms TM and RM. Inasmuch as relay 414 is released at this time, 20 it will be apparent that polarized relay 207 will not close its lower contact when the relay of the receiving mechanism RM, similar to relay 308, is operated, and therefore the conductor 223 will not be grounded to 25 operate relay 112. Since relay 416 is operated, the positive battery connected to the left-hand alternate contact of this relay will cause the relay 207 to ground the conductor 224 after the relay of the receiving mechanism RM, similar to relay 310, is operated. The grounding of the conductor 224 at this time has no effect since relay 112 is not operated. During the operation of the 30 transmitting mechanism TM, the conductor 317 is grounded, as previously described, to short circuit relay 413 through the right-hand contact of relay 416, whereupon relay 413 releases to cause the deenergization of 35 relay 416 and the relay of the transmitting mechanism TM corresponding to relay 200. Relays 411 to 416 and relay 419 are now in 40 their normal condition.

Upon observing the lighted condition of 45 the lamp 404, the operator at office Y withdraws the plug 407 from jack 408, thereby effecting the release of relays 403 and 405 and the extinguishment of the lamp 404, whereupon the apparatus of Fig. 4 is again 50 in its normal condition.

At the time that relay 410 released following the deenergization of relay 400, relay 508 of the toll switching trunk M also released. A circuit for supervisory lamp 506 55 is then established extending from grounded battery, through the lamp 506, the right-hand alternate contact of relay 502, the resistance 507, and normal contact of relay 508. The lamp 506 is lighted in this circuit, 60 and the operator at office Z upon observing the lighted condition of this lamp withdraws the plug 500 from the jack 501, thus causing the release of relay 502 to extinguish the lamp 506. Cut-off relay 503 is also released 65 when plug 500 is withdrawn from jack 501.

The toll switching trunk M and the substation line apparatus is now restored to normal.

Subscriber at substation S recalls the operator at office X. 70

Should the subscriber at substation S before terminating the call desire to communicate with the operator at office X, this may be done by repeatedly opening and closing the switch hook contact at substation S. It will be remembered that while the receiver at the called substation is off the switch hook and the switch hook contact is closed, relays 410 to 416 and relay 419 are released. 75 Upon the first opening of the switch hook contact at the substation, supervisory relay 512 is released to cause the deenergization of relay 509, whereupon relays 508 and 410 are brought into series relation and relay 410 is 80 energized. When the alternate contact of relay 410 closes, relays 411, 412, 413 and 419 are energized over previously described circuits, relays 412 and 413 thereupon locking. The energization of relay 412 closes the previously described energizing circuit for relay 414 and the relay of the transmitting mechanism TM, similar to relay 200, whereupon a series of impulses is transmitted by 85 the mechanism TM over the path P to the receiving mechanism RM, the transmission of said series of impulses resulting in the grounding of the conductor 223, and energization and locking of relay 112 and operation and immediate release of relay 115, 90 following which relays 113 and 114 operate. The ground at the contact of relay 114 is then extended through the left-hand normal contact of relay 115 and through the resistance 111 to energize marginal relay 102 and 95 light the lamp 117. During the transmission of the first series of impulses, ground is connected to the conductor 316 and extended through the right-hand contact of relay 414 100 to release relay 412, following which the relay 414 is released in a manner which is now believed to be well understood. At the termination of the transmission of this series of impulses, relays 410, 411, 413 and 419 are energized, relay 413 being locked. 105

The first closure of the switch hook contacts at substation S following the first opening thereof again causes supervisory relay 512 to operate, whereupon supervisory relay 410 releases to open the circuits for 110 relays 411 and 419. Although relay 411 is made slow to release, it is sufficiently fast in its operation to follow the opening and closing of the switch hook contacts at substation S, but relay 419 is made very slow to 115 release so that the same will maintain its contact closed during the short periods when the alternate contact of supervisory relay 410 is open while the subscriber is repeatedly opening and closing the switch hook 120 125 130

contacts. Therefore, in response to the release of relay 410, relay 411 releases to close its contacts, but inasmuch as relay 419 does not close its contact, it will be apparent that 5 the ground connected to the normal contact of relay 410 upon release thereof will have no effect since this ground is connected to the contact of relay 419 which is open. When the switch hook contacts at substation 10 S are again opened, relay 410 responds by closing its alternate contact to again close the holding circuit for relay 419 before the latter relay can fully release. The connection of ground to the alternate contact of 15 relay 410 again establishes the energizing circuits for relays 411 and 412, whereupon these relays again operate as before. The second operation of relay 412 initiates the transmission of a second series of impulses 20 from office Y to office X which again results in the grounding of conductor 223 and the energization of relay 115. Relays 112, 113 and 114 being energized at this time, grounding of the conductor 223 has no effect 25 upon the relay 112. Relay 115, upon being energized, locks through its left-hand winding and inner left-hand contact to ground at the contact of relay 114. Upon the closure 30 of the outer alternate contact of relay 115, the interrupter 116 is connected in circuit with the resistance 111 to the winding of marginal relay 102, and each time the brush of the interrupter 116 engages a non-grounded segment, the resistance 111 is 35 removed from the circuit of the marginal relay and said relay thereupon releases to extinguish the lamp 117. When a grounded segment of the interrupter 116 is engaged by the brush of the interrupter, it will be 40 obvious that the lamp 117 will be lighted. When relay 115 operates, it opens at its right-hand normal contact the circuit of the slow release relay 113, which, after an interval, releases to cause the deenergization 45 of the slow release relay 114. When this relay releases, ground is removed from its contact, and the locking circuit of relay 115 is opened and this relay thereupon restores 50 to disconnect the interrupter 116 from the circuit of the marginal relay 102. The time interval between the energization of relay 115 and the release of relay 114 is sufficient to cause the lamp 117 to be flashed 55 several times before the interrupter 116 is disconnected from the circuit of the relay 102, and while this is occurring, the switch hook contacts at substations S have again been opened and closed to cause the transmission of another series of impulses from 60 office Y to office X, which again results in the grounding of the conductor 223 and the reenergization of relay 115. When this relay is released in response to the opening of the contact 114, the energizing circuit for 65 relay 113 is again established through the

right-hand contact of relay 115, and in response to the closure of the contact of relay 113, relay 114 is again energized. Therefore, when relay 115 is energized a second time in response to the grounding of the 70 conductor 223, said relay 115 is again locked to ground at the contact of relay 114. The second energization of relay 115 again connects the interrupter 116 in circuit with relay 102, whereupon the lamp 117 is again 75 flashed. This operation continues as long as the subscriber at substation S opens and closes the switch hook contacts thereat, and the operator at office X upon observing the 80 flashing of the lamp 117, may communicate with the subscriber at substation S by operating the listening key 119 at the cord circuit A.

If after repeatedly opening and closing 85 of the switch hook contacts at substation S, the subscriber thereat should leave said contacts closed, that is, keep the receiver off the switch hook, supervisory relay 512 will be energized, and the supervisory relay 410 permanently released. Following the deenergization of relay 410, relay 411 releases and thereafter relay 419 closes its contact since the alternate contact of relay 410 now remains opened. When the contact of relay 419 is closed, ground is extended through 90 the normal contact of relay 410, the right-hand contact of relay 411, the contact of relay 419, the right-hand contact of relay 413, which was locked upon the first energization of relay 412, and from thence over the previously described circuit for relay 416 and the relay of the transmitting mechanism TM, similar to relay 200. With relay 416 operated, a series of impulses is 95 now transmitted from office Y to office X, similar to a previously transmitted series, which results in the grounding of the conductor 224. At this time, relays 112, 113 and 114 are operated, but relay 115 is released. Therefore, the ground on the conductor 224 is extended through the right-hand contact and winding of relay 112 to cause the release of said relay, which is followed by the deenergization of relays 113 and 114. When the latter relay releases, 100 ground is disconnected from the circuit of relay 102 including the resistance 111, and the lamp 117 is permanently extinguished. During the transmission of this last series of impulses to office X to extinguish the lamp 117, conductor 317 is grounded and the ground connected thereto is extended to the winding of relay 413 through the right-hand contact of relay 416, whereupon relay 413 releases. Following this, relay 416 deenergizes as previously described. 105

If after repeatedly opening and closing 110 the switch hook contacts at substation S, the subscriber thereat should replace his receiver on the switch hook to permanently 115

- open said contacts, relay 410 operates to maintain closed the holding circuit for relay 419 and to again cause the energization of relays 411, 412 and 413, whereupon another series of impulses is transmitted to office X to ground the conductor 223, and during the transmission of this series of impulses, relays 412 and 414 are released as before described. The grounding of the conductor 223 again causes the energization of relay 115 to connect the interrupter 116 in series with resistance 111, whereby lamp 117 continues to flash until relay 115 releases in response to the deenergization of relay 114. When relay 115 releases, relays 113 and 114 again operate, and the ground at the contact of relay 114 is now extended through the left-hand normal contact of relay 115, and from thence over the previously described circuits of the resistance 111, to battery through the winding of the marginal relay 102. This circuit is now maintained closed so that the lamp 117 will burn continuously, since no more series of impulses are transmitted from office Y to office X to again energize relay 115. The continued lighting of the lamp 117 now serves as a disconnect signal to the operator at office X, whereupon she proceeds to release the connection in the manner which has already been described.

Simultaneous or contemporaneous calls initiated at office X.

- 35 Should the jacks of two or more transmission lines at office X be plugged into simultaneously, the common conductor 108 will be grounded by the individual mechanisms of each line, and hence relay 200 will be operated to initiate the transmission of a series of impulses from office X to office Y in the same manner as previously described. When the group of relays of the transmitting mechanism at office X, individual to the line 40 which is first in the order of appearance, operates, the energization of the relay individual to said line, similar to relay 107, causes the transmission of the positive impulse over the common path P, which results in the energization of the relay individual to said line, similar to the relay 400, and the consequent lighting of the guard lamp individual to said line. In the same manner a positive impulse is transmitted 45 over the path P when the group of relays, of the transmitting mechanism individual to the next line in the order of appearance, operates. Thus, during the one complete operation of the transmitting and receiving 50 mechanisms it will be apparent that several positive impulses may be transmitted over the common signaling path to effect the operation of a like number of guard lamps at office Y, individual to the various lines which have been taken for use.
- If, after a call has been initiated at office X and the operation of the transmitting mechanism has been started, other lines should be taken for use contemporaneously with the operation of said transmitting mechanism, it will be obvious that characteristic impulses for said other lines will be transmitted over the common signaling path provided that the relays of said other lines similar to relay 107 have been operated before the associated groups of relays of the transmitting mechanism individual to said other lines are energized.
- Operation of system with circuits arranged in accordance with Fig. 9.*
- With Figs. 6 and 7 introduced into the circuit in place of Figs. 2 and 3, when the operator at office X initiates a call by inserting plug 100 into jack 101, relay 103 operates as before and establishes the circuit for relay 107 which in this case now extends over the common conductor 108, and through the winding of relay 601 to grounded battery. Relays 107 and 601 operate, and the latter in closing its contact establishes an obvious operating circuit for relay 604. The closure of the contact of relay 604 connects the ground at the contact of relay 601 through the contact of relay 604, and from thence to grounded battery, through the winding of relay 603, which is thereupon energized. Following the energization of relay 603, relay 602 operates over a circuit traceable from grounded battery, through the winding of relay 602, and the contacts of relays 603, 604 and 601 to ground. The closure of the contact of relay 601 also establishes a circuit extending from ground, through the contact of relay 601, normal contacts of relays 629, 625, 621, 617, 613 and 609 in series, and the winding of relay 632 to grounded battery. Relay 632 energizes and locks through its winding and contact to ground at the contact of relay 631. When relay 602 operates, ground at the contact of relay 601 is extended through the contacts of relays 604, 603 and 602, and from thence to grounded battery, through the right-hand normal contact and winding of relay 605. Relay 605 energizes and locks through its winding, and right-hand alternate contact to ground at the contact of relay 631. The closure of the outer left-hand alternate contact of relay 605 establishes a circuit for relay 633 extending from grounded battery through the winding of relay 633, the outer left-hand normal contact of relay 607, the outer left-hand alternate contact of relay 605, and the contact of relay 601 to ground. Relay 633 energizes and locks through its right-hand contact to ground at the contact of relay 631. The operation of relay 633 has no immediate effect. Upon energization of relay 605, a circuit is also established from

negative battery, through the left-hand normal contact of relay 608, the inner left-hand normal contact of relay 607, the inner left-hand alternate contact of relay 605, and
 5 from thence over one path through the lower winding of the polar relay 600, and the artificial line to ground, and over another path through the upper winding of relay 600, common signaling conductor P', and the
 10 windings of the polarized relay 700 to ground through the artificial line. This impulse of current of negative polarity transmitted over the path P' causes polarized relay 700 to close its upper contact, whereupon
 15 a circuit is established from ground, through the upper contact of relay 700, and from thence over one path through the right-hand normal contact of relay 706, left-hand normal contact of relay 708, and the left-
 20 hand winding of relay 709 to grounded battery, and over another path through the left-hand contact and right-hand winding of relay 706 to grounded battery, the left winding of relay 706 being short circuited
 25 by the ground at the upper contact of relay 710. Relay 706 energizes in the circuit established through its right-hand winding, and in so doing disconnects ground from the left-hand winding of relay 709, and also re-
 30 moves the short circuit from its own left-hand winding so that said relay 706 will be held energized through both of its windings until the upper contact of relay 700 is opened. Before the right-hand normal contact of relay 706 is opened, relay 709 energizes in the circuit established therefor, and locks through its right-hand winding and contact to ground at the contact of relay
 35 731. The closure of the right-hand contact of relay 709 also extends the ground from the contact of relay 731, through the windings of relay 708 and 710 to grounded battery. Relays 708 and 710 energize, and the latter relay in closing its left-hand contact
 40 establishes an operating circuit for relay 732 extending from grounded battery, through the winding of relay 732, the left-hand contact of relay 710, and the outer normal contact of slow release relay 714 to ground. Relay 732, in operating, locks through its winding and contact to ground at contact of relay 731. The ground now connected to the left-hand contact of relay 710 is also extended through the left-hand
 45 alternate contact of relay 709, and from thence in series through the left-hand normal contacts of relays 713, 717, 721, 725 and 729 to grounded battery through the winding of relay 704. Relay 704 operates, and in closing its contact, effects the operation of relay 703 over the energizing circuit for relay 704. The ground now connected to the contact of relay 704 is extended through the contact of relay 703, when the latter relay operates, and causes the operation of re-
 50 lay 702. When the contact of relay 702 is closed, the before mentioned ground is extended through its contact, and through the left-hand normal contact and winding of relay 705 to grounded battery. Relay 705 70 thereupon energizes and locks through its winding and left-hand alternate contact to ground at the contact of relay 731. The ground which is connected to the contacts of relays 702, 703 and 704 is also extended 75 through the outer right-hand alternate contact of relay 708, which is now energized, and the left-hand normal contact and winding of relay 707 to grounded battery, causing the operation of the latter relay simultaneously with that of relay 705. Relay 707 locks through its winding and alternate contact to ground at the contact of relay 731. The simultaneous operation of relays 705 and 707 prevents the closure of an operating circuit for relay 733. Upon the closure of the right-hand alternate contact of relay 707, an impulse of current is transmitted over the path P' from office Y to office X, the circuit for said impulse extending from the negative pole of battery, through the right-hand normal contacts of relays 712 and 711, the right-hand alternate contacts of relays 707 and 705, and thence over one path 80 through the lower winding of polarized relay 700, and the artificial line to ground, and over another path through the upper winding of relay 700, conductor P', and the windings of polarized relay 600 to ground. This 85 impulse of current causes relay 600 to close 90 its upper contact and thereby establish a circuit extending from ground, through said contact, and from thence over one path through the left-hand normal contact of relay 606, the right-hand normal contact of relay 608, and the right-hand winding of relay 609, and over another path through the right-hand contact and left-hand winding of relay 606, to grounded battery, the right-
 95 hand winding of relay 606 being short circuited by the ground at the upper contact of relay 600 until relay 606 energizes to open its normal contacts. Before this occurs, relay 609 operates in the circuit described 100 therefor, and locks through its left-hand winding and contact to ground at the contact of relay 631. The closure of the left-hand contact of relay 609 causes the operation of relays 608 and 610 in multiple to ground at the contact of relay 631. When 105 relay 610 energizes and closes its right-hand contact, ground is extended from the outer right-hand normal contact of relay 614 to the winding of relay 632, but this relay has already been energized and locked, and therefore the closure of the circuit just referred to has no effect. 110
 When relay 608 operates, relay 607 energizes over a circuit traceable from grounded battery, through the winding and right-hand 115

normal contact of relay 607, the outer left-hand alternate contact of relay 608, and from thence through the contacts of relays 602, 603, 604 and 601 to ground. The operation of relay 607 opens the original energizing circuit for relay 633 but this relay remains locked. However, when relay 608 operated, and before relay 607 opens its normal contacts, positive battery is extended from the right-hand alternate contact of relay 107, through the inner left-hand alternate contact of relay 608, the inner left-hand normal contact of relay 607, left-hand alternate contact of relay 605, and from thence through the windings of polar relays 600 and 700 to ground. This momentary impulse of positive battery transmitted over the path P' and through the windings of relays 600 and 700 causes the latter to close its lower contact and thereby disconnect ground from the upper contact thereof to open the holding circuit of relay 706, which then releases. When relay 700 closes its lower contact, a circuit is established extending from ground through the lower contact of relay 700, the left-hand normal contacts of relays 726, 722 and 718, the inner left-hand normal contact of relay 714, the inner alternate contact of relay 710, and thence through the middle winding of differential relay 400 to grounded battery. Relay 400 energizes and locks, and the energization thereof has the same effect as has been previously described in detail. The impulse of positive current which causes the operation of relay 400 is terminated as soon as the left-hand normal contact of relay 607 is opened by the energization of this relay. As soon as the left-hand alternate contact of relay 607 is closed, an impulse of negative current is transmitted over the path P' by the closure of the circuit extending from negative battery, through the left-hand normal contacts of relays 612 and 611, the left-hand alternate contact of relay 607, the inner left-hand alternate contact of relay 605, and from thence over the previously described path through the relays 600 and 700 to ground. This impulse of current causes the relay 700 to close its upper contact, and thus disconnect ground from the middle winding of the relay 400, which now remains locked. The closure of the upper contact of relay 700 now establishes a circuit extending from ground, through said contact, the right-hand contact of relay 706, the left-hand alternate contact of relay 708, the left-hand normal contact of relay 712, and the left-hand winding of relay 713 to grounded battery. Relay 713 energizes and locks, and in closing its right-hand contact establishes energizing and holding circuits for relays 712 and 714. Ground connected to the upper contact of relay 700 also causes relay 706 to energize, as previously described. The operation of relay 714 opens the original energizing circuit for relay 732, which is now locked. When relay 712 energizes, relay 600 is caused to open its upper contact and restore its armature to neutral position by the momentary ground connected through the normal contact of relay 414, the inner right-hand alternate contact of relay 712, the right-hand normal contact of relay 711, the right-hand alternate contacts of relays 707 and 705, and from thence through the windings of relays 700 and 600 to ground. This momentary ground is connected to relay 600 before the relay 711 opens its right-hand normal contact in response to the energization of said relay by a circuit extending through the winding and left-hand normal contact of relay 711, the outer right-hand contact of relay 712, and thence over the previously described energizing circuit for relays 705 and 707. When the right-hand alternate contact of relay 711 closes, negative battery is extended through the right-hand normal contacts of relays 716 and 715, the right-hand alternate contacts of relays 711, 707 and 705, and from thence through the windings of relays 700 and 600 to ground. This negative impulse of current causes relay 600 to close its upper contact and thereby establish a circuit for energizing relay 613, said circuit being traceable from ground, through the upper contact of relay 600, the left-hand normal contact of relay 606, which deenergized when relay 600 was previously released, the right-hand alternate contact of relay 608, the right-hand normal contact of relay 612, and the right-hand winding of relay 613 to grounded battery. Relay 613 energizes and locks over an obvious circuit, and in closing its left-hand contact establishes obvious energizing and holding circuits for relays 612 and 614. The latter relay, in opening its outer right-hand normal contact, opens the original energizing circuit for relay 632, which is now locked.

The energization of relay 612 connects ground through the normal contact of relay 110, the inner left-hand alternate contact of relay 612, the left-hand normal contact of relay 611, the inner left-hand alternate contact of relay 607, and from thence over the previously described path through the windings of relays 600 and 700. The connection of ground to the relay 700 causes the same to restore and thereby open its upper contact to release relay 706. Immediately following the restoration of relay 700, relay 611 energizes over a circuit traceable from grounded battery, through the winding and right-hand normal contact of said relay, the outer left-hand alternate contact of relay 612, and from thence over the previously described path to ground through contacts of relays 602, 603, 604 and 601. After energizing, relay 611 locks through its

- winding and right-hand alternate contact to ground at the contact of relay 631. When relay 614 operates, a circuit is established extending from ground, through the contact 5 of relay 630, the left-hand normal contacts of relays 626, 622 and 618, the left-hand contacts of relays 614 and 107, and the winding of relay 106 to grounded battery. Relay 106 energizes and locks, as before described, and 10 in opening its normal contact breaks the energizing and holding circuit for relays 107 and 601, these relays thereupon restoring. Removal of ground from the contact of relay 601 opens the original energizing circuits 15 for relays 604, 603 and 602, but these relays are now maintained energized under the control of relay 631, the ground at the contact of the latter relay being connected to the windings of relays 602, 603 and 604 20 through the contact of relay 632, the right-hand alternate contacts of relays 609 and 613, and the right-hand normal contacts of relays 617, 621, 625 and 629.
- When relay 611 closes its left-hand alternate contact, relay 700 is again operated to close its upper contact by a circuit traceable from negative battery, through the left-hand normal contacts of relays 616 and 615, the left-hand alternate contact of relay 611, 25 and from thence over the previously described path through the windings of relays 700 and 600. The ground now connected to the upper contact of relay 700 is extended through the right-hand normal contact of 30 relay 706, the left-hand alternate contacts of relays 708 and 712, the left-hand normal contact of relay 716, and the left-hand winding of relay 717 to grounded battery. Relay 717 is energized and locked through its 35 right-hand winding and contact, and the closure of this contact causes the energization of relays 716 and 718. Relay 706 also operates in response to the connection of ground to the upper contact of relay 700, 40 and remains operated until said relay 700 releases. When relay 716 closes its inner right-hand alternate contact, a momentary ground extending from the normal contact of relay 416 and over the conductor 418 is 45 connected to the mentioned contact of relay 716, and from thence is extended through the right-hand normal contact of relay 715, the right-hand alternate contact of relay 711, and from thence over the previously 50 described path for relays 600 and 700, causing the relay 600 to open its upper contact and thereby release relay 606. This momentary connection of ground to the polarized relays 700 and 600 is discontinued when relay 715 operates in response to the closure 55 of the right-hand alternate contact of relay 716, the circuit for relay 715 being traceable from grounded battery, through the winding and left-hand normal contact of 60 relay 715, the outer right-hand alternate contact of relay 716, and from thence over the previously described path to ground at the contact of relay 701. The closure of the right-hand alternate contact of relay 715 establishes a circuit extending from the negative pole of battery, through the right-hand normal contacts of relays 720 and 719, the right-hand alternate contact of relay 715, and from thence over the previously described path through the windings of the relays 700 and 600 to ground. Relay 600 again closes its upper contact to energize relay 606 and momentarily extend ground through the contact of relay 606, the right-hand alternate contacts of relays 608 and 612, the right-hand normal contact of relay 616, and the right-hand winding of relay 617 to grounded battery. Relay 617 energizes and locks, and through its left-hand contact establishes energizing and holding 75 circuits for relays 616 and 618.
- Assuming that the transmission line next following the line L1 in the order of its appearance is idle, upon the closure of the inner left-hand alternate contact of relay 616, 80 a momentary ground is extended from the normal contact of the relay associated with said next line, similar to relay 107, and then through said contact of relay 616, the left-hand normal contact of relay 615, and from 85 thence over an obvious circuit through the windings of relays 600 and 700 to ground. Relay 700 thereupon releases to open its upper contact whereby relay 706 is again released. Following the connection of ground 90 to the windings of relays 600 and 700, relay 615 energizes over a circuit traceable from grounded battery, through the winding and right-hand normal contact of said relay, the outer left-hand alternate contact of 95 relay 616, the contacts of relays 602, 603 and 604, and from thence over a previously described path to ground at the contact of relay 631, it being understood that the control 100 of relays of the transmitting mechanism at office X has now been transferred from relay 601 to relay 631 due to the release of the former relay, as previously described. Upon energizing, relay 615 locks over an 105 obvious circuit, and in closing its left-hand alternate contact, causes the transmission of a negative impulse of current over the path P', the circuit of said impulse being traceable from negative battery, through the left-hand normal contacts of relays 620 and 619, the left-hand alternate contact of relay 615, and from thence over the previously 110 described path through the windings of relays 600 and 700. Relay 700 responds to this impulse by closing its upper contact to 115 establish the energizing circuit for relay 706, and also extends ground through the right-hand normal contact of relay 706, the left-hand alternate contacts of relays 708, 712 and 716, the left-hand normal contact of re- 120 125 130

lay 720, and the left-hand winding of relay 721 to grounded battery. Relay 721 energizes before the right-hand normal contact of relay 706 is opened and locks through its 5 right-hand winding and contact. The closure of the latter contact establishes energizing and holding circuits for relays 720 and 722. When the inner right-hand alternate contact of relay 720 is closed in response to the energization of this relay, ground is momentarily extended through said contact from the normal contact of a relay of the transmission line following the line L1 in the order of its appearance, similar 10 to relay 414. This ground is now extended through the right-hand normal contact of relay 719, and from thence over an obvious path through the windings, of relays 700 and 600 to cause the latter relay to open its upper contact and release relay 606. The closure of the outer right-hand alternate of relay 720 establishes an energizing circuit for relay 719 through the winding and left-hand normal contact of this relay, 15 and after closing its left-hand alternate contact, said relay 719 is locked. A negative impulse of current is now transmitted from office Y to office X over a path extending from negative battery, through the right-hand normal contacts of relays 724 and 723, the right-hand alternate contact of relay 719, and from thence over the previously described path through the windings of relays 700 and 600 to ground. Relay 600 responds 20 by closing its upper contact to extend ground through the left-hand normal contact of relay 606, the right-hand alternate contacts of relays 608, 612 and 616, right-hand normal contact of relay 620, and the right-hand winding of relay 621 to grounded battery. Relay 621 energizes and locks, and in so doing causes the energization of relays 620 and 622. 25 When relay 620 energizes, the ground connected to the normal contact of the relay associated with the transmission line following the line L1, similar to relay 110, is now extended through the inner left-hand alternate contact of relay 620, the left-hand normal contact of relay 619, and from thence over an obvious path through the windings of relays 600 and 700 to ground, causing relay 700 to restore to normal and thereby release relay 706. Following the connection 30 of ground to the relay 700 through a contact of relay 620, relay 619 energizes and locks over circuits which are now believed to be obvious. A negative impulse of current is now transmitted from office X to office Y, the circuit of said impulse being traceable from negative battery through the left-hand normal contacts of relays 624 and 623, the left-hand alternate contact of relay 619, and from thence over the previously described 35 path through the windings of relays 600 and 700 to ground. Relay 700 closes its upper contact in response to this impulse, and ground at this contact is extended through the right-hand contact of relay 706, the left-hand alternate contacts of relays 708, 712, 716 and 720, the left-hand normal contact of relay 724, and the left-hand winding of relay 725 to grounded battery. Relay 725 energizes and locks, and in so doing causes the operation of relays 724 and 726. The closure of the inner right-hand alternate contact of relay 724 connects ground to this contact from the normal contact of a relay associated with the transmission line following the line L1, similar to relay 416, and this ground is thereupon extended through the right-hand alternate contact of relay 719, and from thence over an obvious path through the windings of relays 700 and 600 to ground, causing the latter relay to open its upper contact and release relay 606. Relay 723 then energizes over an obvious circuit through the outer right-hand alternate contact of relay 724, and locks through its winding and left-hand alternate contact to ground at the contact of relay 731. When the right-hand alternate contact of relay 723 closes, the negative battery is connected through the right-hand normal contacts of relays 728 and 727, and from thence through the right-hand alternate contact of relay 723 over an obvious path through the windings of relays 700 and 600 to ground. The impulse of current thus transmitted causes relay 600 to close its upper contact to again energize relay 606 and to also extend ground through the left-hand normal contact of the latter relay before said contact is opened, and from thence through the right-hand alternate contacts of relays 608, 612, 616 and 620, the right-hand normal contact of relay 624, and the right-hand winding of relay 625 to grounded battery. Relay 625 energizes and locks, and causes the operation of relays 624 and 626. 40 45 50 55 60 65 70 75 80 85 90 95 100 105 110 115 120 125 130

Ground at the normal contact of the relay associated with the next or, as shown, the last transmission line in the order of appearance, similar to relay 107, is now extended through the inner left-hand alternate contact of relay 624, the left-hand normal contact of relay 623, and from thence over an obvious path through the windings of relays 600 and 700. Relay 700 releases to open its upper contact, and thereby causes the release of relay 706. Following the operation of relay 624, relay 623 operates and locks over obvious circuits, whereupon negative battery is connected through the left-hand normal contacts of relays 628 and 627, the left-hand alternate contact of relay 623, and from thence over an obvious circuit through the windings of relays 600 and 700 to ground. This negative impulse of current causes relay 700 to close its upper contact.

tact and thereby energize relays 706 and 729, the circuit for the latter relay extending through the left-hand alternate contacts of relays 708, 712, 716, 720 and 724. Relay 5 729, in energizing, locks and establishes operating circuits for relays 728 and 730. Relays 728, in closing its left-hand contact, establishes an obvious operating circuit for slow operating and release relay 731 which, 10 in energizing, removes ground from its contact to cause the release of all of the relays of the receiving mechanism at office Y, which have been operated during the transmission of the series of impulses. However, 15 before the ground is removed from the contact of relay 731, relay 727 is operated and locked by the closure of the outer right-hand alternate contact of relay 728. Before the right-hand normal contact of relay 727 20 is opened, however, ground is extended through this contact from the inner right-hand alternate contact of relay 728, and from thence over an obvious path through the windings of relays 700 and 600 to cause 25 the latter relay to open its contact, whereby relay 606 is released. Then, when this ground is disconnected from the polar relays by the opening of the right-hand normal contact of relay 727, negative battery 30 is extended from the normal contact of relay 733 through the right-hand alternate contact of relay 727, and from thence over an obvious path through the windings of relays 700 and 600 to ground, causing relay 35 600 to again close its upper contact after which relay 731 fully energizes to open its contact. When relay 600 operates, relays 606 and 629 are operated, the circuit for the latter relay extending through the left-hand 40 normal contact of relay 606 before this contact is opened by the energization of said relay 606, and the right-hand alternate contacts of relays 608, 612, 616, 620 and 624. Relay 629 energizes and locks, and causes the 45 operation of relays 628 and 630. The closure of the right-hand contact of relay 628 causes the operation of slow operating and releasing relay 631, whereupon ground is removed from the contact of the latter relay to cause 50 the release of all of the relays of the transmitting mechanism at office X. Before relay 631 opens its contact, the closure of the inner right-hand alternate contact of relay 628 connects ground through the left-hand 55 normal contact of relay 627 to the windings of relays 600 and 700 to cause the latter relay to restore and thereby release relay 706. Following this, relay 627 operates in an obvious circuit and locks to ground at the 60 contact of relay 631, which has not yet fully energized, whereupon ground is extended through the left-hand alternate contacts of relays 633 and 627, and from thence over the previously described path through the wind-

ings of relays 600 and 700. This ground 65 has no effect upon the relay 700 since it is already in its normal condition. The entire series of impulses has now been transmitted from office X to office Y, and the transmitting and receiving mechanisms have completed their cycles and been restored to normal. 70

It is believed that with an understanding of the previous description, the operation of transmitting impulses from office Y to office 75 X, as when the operator at office Y connects the line L1 with the toll switching trunk M, and when the subscriber at substation S recalls the operator at office X, or replaces his receiver upon the switch hook, will be 80 fully understood, it being noted that similar relays in Figs. 6 and 7 are numbered alike, with the exception of the hundreds digits. Likewise, the manner in which ringing and disconnect signals are transmitted from office 85 X to office Y will be fully understood from the previous description.

It will also be obvious that in employing the mechanisms of Figs. 6 and 7, a plurality of signaling devices at office Y, such 90 as the guard lamps, will be operated if calls are initiated simultaneously on two or more lines at office X, or if after the initiation of one call, other lines at office X should be taken for use contemporaneously with the 95 operation of the transmitting and receiving mechanisms, provided said other lines are seized and the relays associated therewith, similar to relay 107, are energized before the groups of relays of the transmitting mechanisms associated with said lines are operated. 100

What is claimed is:

1. In a telephone system, a plurality of transmission lines, a signaling path common 105 to said lines extending between two offices, a signaling device at one office, groups of relays each individual to one of said lines operable to transmit a series of impulses over said signaling path, means responsive to said series of impulses for operating said signaling device, switching devices for controlling the operation of said groups of relays, means for initially rendering one of said switching devices operable to control said groups of relays, and means for thereafter transferring the control of said groups of relays to another switching device. 110

2. The method which comprises transmitting a series of impulses over a signaling path in response to the seizure of one circuit, translating said series into a signal, and translating said series into other signals when other circuits are seized contemporaneously 125 with the transmission of said series of impulses.

3. The method of transmitting impulses

- over a signaling path common to a plurality of toll transmission lines, which comprises transmitting an impulse over said path, receiving said impulse, and, in response to the receipt of such impulse, transmitting a second impulse back over said path to control the transmission of a third impulse thereover.
4. The method of transmitting impulses over a signaling path common to a plurality of toll transmission lines, which comprises transmitting an impulse over said path, receiving said impulse and, in response to the receipt of such impulse, transmitting a second impulse to control the transmission of a third impulse over said path.
5. The method of transmitting impulses over a signaling path common to a plurality of transmission lines, which comprises initially transmitting an impulse by the seizure of one of said lines and thereafter controlling the transmission of another impulse by the receipt of the first-named impulse at a distant point.
- 25 6. The method of transmitting impulses over a signaling path common to a plurality of transmission lines which comprises seizing one of said lines to initially transmit an impulse from one point over said path to a distant point and then transmitting an impulse from said distant point over said path to control the transmission of another impulse from the first-named point.
- 35 7. The method of transmitting impulses over a signaling path common to a plurality of transmission lines, which comprises seizing one of said lines to initially transmit an impulse from one point over said path to a distant point and then controlling the transmission of an impulse by the receipt of the first-named impulse to control the transmission of another impulse from the first-named point.
- 45 8. In a telephone system, a plurality of transmission lines, a signaling path common to said lines extending between two offices, a signaling device, a transmitting mechanism operable to transmit a series of impulses over said signaling path, an impulse receiving mechanism operable in response to each impulse transmitted by said transmitting mechanism for controlling the transmission of the next impulse of said series, and means for operating said signaling device in response to said series of impulses.
- 50 9. In a telephone system, a plurality of transmission lines, a signaling path common to said lines extending between two offices, a signaling device, a transmitting mechanism including a plurality of relays operable to transmit a series of impulses over said signaling path, and impulse receiving mechanism operable in response to each impulse transmitted by said transmitting mech-
- anism for controlling the transmission of the next impulse of said series, and means for operating said signaling device in response to said series of impulses.
- 55 10. In a telephone system, a plurality of transmission lines, a signaling path common to said lines extending between two offices, a signaling device, a transmitting mechanism operable to transmit a series of impulses over said signaling path, a receiving mechanism including a plurality of relays certain of which are operable in response to each impulse transmitted by said transmitting mechanism for controlling the transmission of the next impulse of said series, and means for operating said signaling device in response to said series of impulses.
- 60 11. In a telephone system, a plurality of transmission lines, a signaling path common to said lines extending between two offices, a signaling device, a transmitting mechanism for transmitting a series of impulses over said path and including groups of relays, each group being operable to control the transmission of one of said impulses, an impulse receiving mechanism operable in response to each impulse transmitted by said transmitting mechanism for controlling the operation of one group of relays, and means for operating said signaling device in response to said series of impulses.
- 65 12. In a telephone system, a plurality of transmission lines, a signaling path common to said lines extending between two offices, a signaling device, a transmitting mechanism operable to transmit a series of impulses over said signaling path, an impulse receiving mechanism including a plurality of groups of relays, each group being responsive to the transmission of an impulse from said transmitting mechanism to control the transmission of another impulse from said transmitting mechanism, and means for operating said signaling device in response to said series of impulses.
- 70 13. In a telephone system, a plurality of transmission lines and a signaling path common thereto extending between two offices, a signaling device, an impulse transmitting mechanism for transmitting impulses over said signaling path, means for receiving said impulses and for controlling the transmission thereof, and means operable in response to the received impulses for operating said signaling device.
- 75 14. In a telephone system, a plurality of transmission lines and a signaling path common thereto extending between two offices, a signaling device, an impulse transmitting mechanism for transmitting impulses over said signaling path, means for receiving said impulses, and operable in response to each impulse transmitted for controlling the transmission of another im-

pulse by said transmitting mechanism, and means responsive to the transmitted impulses for operating said signaling device.

15. In a telephone system, a plurality of transmission lines and a signaling path common thereto extending between two offices, a plurality of signaling devices, means for transmitting a series of impulses over said signaling path, means for receiving said impulses and operable in response to each im-

pulse transmitted for controlling the transmission of the next impulse of the series, and means for operating a plurality of said signaling devices in response to a single series of impulses.

15

In witness whereof, I hereunto subscribe my name this 28th day of February, A. D. 1922.

HUGH D. MACPHERSON.
